LOCK CAP FOR GAS TANKS

Fred E. Rockhill, Ketchikan, Territory of Alaska

Application April 1, 1933, Serial No. 664,012

1 Claim. (Cl. 220—33)

This invention relates to the gas tanks of automobiles though the invention might be applied to other structures and the general object of the invention is to provide a cap for the gasoline tank 5 filling openings of automobiles which is adapted to be locked in place to prevent the theft of gasoline from the tank.

A further object is to provide a cap of this character which is adapted to be unlocked preferably by the same key as is used for unlocking or locking the ignition switch and further to provide a cap which is adapted to be inserted in the neck of the gas tank and locked therein or when unlocked entirely removed from the neck 15 of the gas tank, this portion of the cap having a hinged closure which, when the body of the cap is inserted within the neck of the gas tank and the key removed, may be swung over to entirely protect the parts from weather.

20 Other objects will appear in the course of the following description.

The invention is illustrated in the accompanying drawing, wherein:—

Figure 1 is a top plan view of my improved cap; 25 Figure 2 is a vertical sectional view through the neck or filling opening of a gas tank showing the cap in place therein with the closure opened and the key inserted.

Referring to the drawing, it will be seen that 30 the body of the cap includes a top plate 10 having its central portion upwardly bulged as at 11, the margin of the cap being downwardly turned at 12 to fit over the neck A of the tank B. Disposed within this casing plate 10 is a lock casing 12 which may be held to the casing plate 10 in any 35 suitable manner as by the rivets 13 or by welding, soldering or the like. The lock casing 12 is less in diameter than the extreme diameter of the casing plate 10 and a gasket 14 is disposed at 40 the upper end of the portion 12 between this portion 12 and the lock casing. The neck A at its upper end bears against this gasket 14 when the cap is in place as shown in Figure 2. This neck A is provided with the inwardly extending shoulder or flange a and the lock casing is provided 45 with a plurality of bolts, two of which are shown and designated 15 which are beveled on their under faces at their extremities and which are adapted to engage beneath this flange or shoulder 50 a when the cap is in place. These are spring projected bolts and can only be retracted by means of the key 16. Inasmuch as a large variety of locks might be used for this purpose and inasmuch as the detailed construction of the lock 55 forms no part of my invention, I have not illus-

trated the lock mechanism except to show the extremities of the bolts 15 and the lock casing itself.

Preferably the key 16 is the ignition key of the automobile, though I do not wish to be limited to this, and preferably attached to the lower 60 wall 17 of the lock casing is a chain 18 terminating in an anchor 19 having a length greater than the diameter of the neck A so that while the body of the cap may be removed entirely from the neck, it cannot be easily detached from the neck. 65

Attached to the downwardly extending margin 12 of the casing plate 10 as by welding or in any other suitable manner is a vertically extending wall 20 having a length less than half of the circumference of the portion 12. This wall 20 70 at one end terminates in a hinge element 21 and engaged with this hinged element is an arcuate wall 22 which is complementary to the wall 20 and which has a length greater than half of the circumference of the flange 12. Welded or soldered to this wall is the plate 23 having a downwardly extending flange 24 at its margin, which flange is attached to the wall 22 and soldered, welded or otherwise attached to this plate 23 is a cap 75 plate 25 which is slightly domical and which extends beyond the flange 24 on all sides so as to form a protecting cap for the structure. It will be seen that when the key 16 is removed, this closure section formed of the parts 22, 23 and 25 may be rotated upon its hinge to entirely cover 80 the body section of the cap and that when it is swung to the position shown in Figure 2, access may be had to the body section to insert the key 16, retract the latch bolts 15 and remove the body sections from the neck to permit the tank 90 B to be filled with fuel.

It will likewise be seen that the wall 22 must yield slightly to permit the cap section to be closed around the body section and after it has been closed, this wall 22 will slightly contract 95 through its own resiliency and thus hold the cap section closed over the body section.

One of the advantages of this invention is that it requires that the ignition circuit shall be broken and the engine, therefore, stopped before it is 100 possible for the attendant at a gas station to fill the tank with gasoline. Many accidents have occurred in consequence of the motor running while the gasoline tank is being filled and this structure will entirely prevent any accidents of this kind 105 happening because, if the ignition switch key is used for opening the cap, the engine must be shut off before fuel can be filled into the tank.

It will further be seen that I have provided a very simple and easily applied cap which is ca- 110

pable of being entirely removed from its obstructing position over the neck of the gas tank so as to form no impediment to the insertion of the filling hose and that this cap may be readily removed and readily applied and that the lock mechanism is entirely protected from the weather.

While I have illustrated certain details of construction and arrangements of parts, I do not wish to be limited thereto as obviously many changes might be made therein without departing from the spirit of the invention as defined in the appended claim.

What is claimed is:—

15 A cap for the gas tanks of automobiles including a lock casing, an outer casing extending over

the top of the lock casing and outward beyond the circumference thereof and then extended downward in spaced relation to the lock casing and adapted to extend downward over a filling neck, an arcuate wall exterior to and extending upward from the periphery of the outer casing and less in length than one-half the circumference of the outer casing, an arcuate wall hinged to one end of the first named wall having swinging movement in a plane at right angles to said wall and having a length greater than one-half the circumference of the outer casing, a cap carried by said wall and adapted when the wall is swung inward to embrace the outer casing to extend entirely over and project beyond the outer casing.

FRED E. ROCKHILL.
